HIS ATTORNEYS.

UNITED STATES PATENT OFFICE.

HARRY T. RANDLE, OF LAWRENCE, KANSAS.

GOLF-BALL MARKER.

Application filed June 1, 1925. Serial No. 34,012.

To all whom it may concern:

Be it known that I, HARRY T. RANDLE, a citizen of the United States, residing at Lawrence, Douglas County, Kansas, have 5 invented a new and useful Golf-Ball Marker, of which the following is a specification.

This invention relates to golf ball markers.

10 An object of the invention is to provide an improved golf ball marker in which the golf ball is supported upon a pair of circumferentially grooved rollers in exact radial alinement with the pivotally supported 15 manipulative name plate or die, in combination with clamping means for clamping the golf ball in position and rotating the same uniformly with the movement of the name plate or die, whereby a name or other 20 identifying device is impressed upon the periphery of the golf ball.

Another object of the invention is to provide an improved golf ball marker possessing the characteristics and advantages 25 of the invention herein shown and described.

In the drawing Fig. 1 is a plan view of my improved golf ball marker.

Fig. 2 is a side elevation.

Fig. 3 is a front elevation with some of the 30 parts shown in section.

The base 1 is preferably a casting having a pair of spaced standards 2 between which are a pair of parallel flanges 3. One of the standards 2 has a threaded hole through 35 which a rod 4 is screwed to the outer end of which is rigidly connected a knurled hand wheel or knob 5 providing means for rotating said rod.

An inwardly facing concave clamping 40 member 6 is swiveled upon the inner end of the rod 4 above the plane of the upper edges of the flanges 3.

A rod 7 extends through a hole in the other standard 2 in axial alinement with 45 the rod 4 and is freely rotative. An inwardly facing concave clamp member 8 is rigid with the inner end of the rod 7 in cooperative relationship to the clamp member 6 so that a golf ball A placed between said 50 clamp members will extend into the concavities thereof and may be clamped by screwing the rod 4 inwardly to press the clamp member 6 against the golf ball and to press the golf ball against the clamp mem-

ber 8. A sleeve 9 is upon the rod 7 between 55 the clamp member 8 and the standard 2 to prevent outward movement of the rod 7. A collar 10 is on the rod 7 against the outer side of the standard 2, and the end of said rod 7 is equipped with a rigidly connected 60 handle member 11 which may be in the form of a knurled hand wheel or knob as shown.

The flange 3 supports a pair of parallel axles 12, each of which supports a freely 65 rotative circumferentially grooved roller 13. The circumferential grooves in the rollers 13 are preferably formed on a radius of curvature which is the same as the radius of curvature of the periphery of the golf ball. 70

The rear portion of the base 1 is provided with a pair of standards 14 supporting a rod 15 parallel with the rods 4 and 7 and with the axle members 12. A bracket 16 is pivotally supported by the rod 15 and carries a removable pivot 17 near its upper end. A lever 18 has one end pivoted upon the pivot 17 and its opposite end provided with a handle 19. The lower side of the lever 18 is formed with a pair of parallel flanges 20 80 designed and adapted to receive between them a name plate or die 21 and a spacing plate 22. A clamp screw 23 screws through a hole in one of the flanges 20 and presses the spacing plate 22 against the name plate 85 or die 21 and securely holds the latter in position.

In operation the golf ball to be marked is placed upon the rollers 13 and in the concavity of the clamp member 8. The rod 4 90 is then screwed inwardly to cause the clamp member 6 to engage and clamp the golf ball rigidly between the two clamp members and in which position it is upon the freely rotative grooved rollers 13. The name plate or die 21 is then pressed upon the golf ball and moved forwardly or rearwardly as desired, while at the same time the rod 7 is turned, which causes the rigidly connected clamp member 8 to rotate the golf ball uniformly with the movement of the name plate or die during which rotation of the ball the clamp member 6 and the rollers 13 turn with it. The name plate or die and the golf ball may be operated back and forth as desired to cause the name or other device of the name plate or die to be impressed clearly upon the golf ball. After this has been 100 105

done the golf ball is released by turning the rod 4 and raising the lever 18, permitting the golf ball to be removed and another to be inserted and marked.

5 From the foregoing it will be seen that my invention is a highly efficient marker by which the golf ball may be freely rotative in conformity with the movement of the name plate or die, and that the supports for 10 the golf ball are themselves rotative thus overcoming frictional resistance as a result of all of which the marking operation is facilitated.

I do not restrict myself unessentially, but 15 what I claim and desire to secure by Letters Patent is:—

1. A golf ball marker comprising a pair of ball supporting rollers supported for rotation on parallel axes, a pair of rotative 20 clamping elements for clamping between them a golf ball supported upon said rollers, and means for making an impression upon the periphery of the golf ball.

2. A golf ball marker comprising a pair of peripheral grooved rollers mounted for rotation upon parallel axes, means for rotating a golf ball supported upon said rollers, and means for making an impression upon the periphery of the golf ball.

30 3. A golf ball marker comprising a pair of peripherally grooved rollers supported upon parallel axes and arranged to support a golf ball, a laterally immovable clamp arranged to engage one side of the 35 golf ball supported upon said rollers, a clamp movable to press against the opposite side of the golf ball, means for rotating said first clamp and thereby the golf ball, and a device for making an impression upon the 40 periphery of the golf ball during rotation of the golf ball as aforesaid.

4. A golf ball marker comprising a pair of rollers supported upon parallel axes and each having a peripheral groove arranged to 45 receive and retain a golf ball, devices for clamping and rotating the golf ball upon said rollers, a device for making an impression upon the periphery of the golf ball when the ball is rotated as aforesaid, and means for pressing said device against the 50 golf ball.

5. A golf ball marker comprising a pair of rollers supported upon parallel axes and each having a peripheral groove arranged to 55 receive and retain a golf ball, devices for clamping and rotating the golf ball upon said rollers, a device for making an impression upon the periphery of the golf ball when the ball is rotated as aforesaid, and means for pressing said device against the 60 golf ball and moving said device to prevent sliding contact thereof with the golf ball.

6. A golf ball marker comprising a pair of parallel freely rotative rollers having peripheral grooves therein arranged to receive 65

and support a golf ball, a rotative rod, means for preventing longitudinal movement of said rod, a clamping device rigid with the inner end of said rod and rotative therewith, an additional clamping device movable to position to clamp the golf ball between it and the first named clamping device and upon said rollers, means for rotating said rod and thereby the golf ball and said rollers, a device for making an impression upon the periphery of the golf ball, and means for operating said device in conformity with the rotation of the golf ball.

7. A golf ball marker comprising a rotative rod, means for preventing longitudinal movements of said rod, a concave clamping device rigid with one end of said rod, a member rigid with the other end of said rod for rotating said rod and said clamping device, a longitudinally movable rod in axial alinement with said first named rod, a concave clamping device swiveled on one end of said second rod for clamping a golf ball between it and the first named clamping device when said second rod is moved toward said first rod and arranged to rotate with the golf ball when said first rod and first clamping device are rotated, means for operating said second rod, a longitudinally movable support, and an impression making device carried by said support arranged to make an impression upon the surface of the golf ball when said golf ball is rotated as aforesaid.

8. A golf ball marker comprising a rotative rod, means for preventing longitudinal movements of said rod, a concave clamping device rigid with one end of said rod, a member rigid with the other end of said rod for rotating said rod and said clamping device, a longitudinally movable rod in axial alinement with said first named rod, a concave clamping device swiveled on one end of said second rod for clamping a golf ball between it and the first named clamping device when said second rod is moved toward said first rod and arranged to rotate with the golf ball when said first rod and first clamping device are rotated, means for operating said second rod, a longitudinally movable support, an impression making device carried by said support arranged to make an impression upon the surface of the golf ball when said golf ball is rotated as aforesaid, and a pair of peripherally grooved rollers for supporting a golf ball in position to be engaged by said clamping devices.

9. A machine of the character described comprising rotative supports for supporting a golf ball in position to be engaged by clamping devices, clamping devices for engaging and rotating a golf ball upon said supports, a longitudinally movable support, and a device supported by said longitudinally movable support for making an impres-

sion upon the surface of the golf ball upon said first named supports when said golf ball is rotated by said clamping devices.

10. A machine of the character described comprising rotative supports for supporting a golf ball, clamps for engaging a golf ball, means for rotating a golf ball, a longitudi-

nally movable support, means for removably supporting an impression making device in connection with said last named support, and means for operating said last named support in conformity with the rotation of the golf ball. 10

HARRY T. RANDLE.
